UNITED STATES PATENT OFFICE.

GUSTAV A. BADER, OF ROCHESTER, NEW YORK.

NOSE-CLAMP FOR EYEGLASSES.

1,182,521.

Specification of Letters Patent.

Patented May 9, 1916.

Application filed February 19, 1913. Serial No. 749,557.

To all whom it may concern:

Be it known that I, GUSTAV A. BADER, a citizen of the United States, and resident of Rochester, in the county of Monroe and 5 State of New York, have invented certain new and useful Improvements in Nose-Clamps for Eyeglasses, of which the following is a specification.

This invention relates to nose-clamps or 10 nose-guards of the type in which a facing of celluloid, or other hard but non-metallic material, is provided at the nose-engaging surface of the nose-clamp, to prevent direct engagement of the metallic parts with the 15 nose, or to increase the adhesion of the nose-clamp to the skin.

Nose-clamps of the type in question are 20 commonly constructed by punching out a piece of sheet-metal and a piece of celluloid, or other hard plastic material, in sheet form, and by then riveting the facing-material to the sheet-metal, the nose-engaging surface of the facing-material being usually 25 corrugated or roughened. In such a construction the edge of the facing-material is usually sharp and more or less rough, as the result of the punching-operation, and the edge of the metal backing or body is uncovered and unprotected. In assembling 30 the parts it is difficult to insure the exact coincidence of their edges when the parts are riveted together, and for this and the foregoing reason the edges of a nose-clamp constructed in this manner present a rough 35 and unfinished appearance, unless subjected to a special finishing operation.

The object of the present invention is to 40 produce a nose-clamp in which these objections are avoided in a novel and simple manner, and without substantial increase in the cost of manufacture.

To the foregoing end I employ, in combination with a sheet-metal body or backing of any ordinary or suitable form, a 45 facing of plastic material, such as any of the well known cellulose compounds, this facing having the general form and dimensions of the metal part, but having a rearwardly-projecting marginal flange which 50 closely embraces the edge of the metal, so as to partly or wholly cover this edge, thus producing a smooth and neat finish, and at the same time assisting in the operation of assembling the parts of the nose-clamp.

55 In the drawings:—Figure 1 is a perspective view, on a greatly enlarged scale, of a

nose-clamp of conventional form embodying the present invention, looking toward the outer surface of the nose-clamp; Fig. 2 is a similar view of a nose-clamp in which the invention is applied to a self-adjusting nose-pad forming a portion only of the nose-engaging surface; Fig. 3 is a section on the line 3—3 in Fig. 1 looking downwardly; and Fig. 4 is a perspective view of 65 the facing-member of the nose-pad shown in Fig. 2, looking toward the inner surface, and with the upper portion of the member broken away.

In Figs. 1 and 3 the invention is illustrated as embodied in a nose-clamp of the well known form in which a single, rigid nose-engaging member is employed. The body 5 of the nose-clamp is formed of sheet-metal in the usual manner, while its inner 70 surface is covered with a facing 6 of celluloid or other suitable plastic material, this facing being fixed to the metal, in the usual manner, by means of rivets 7. In accordance with the present invention the facing- 75 member is recessed at its outer surface, so as to receive the body 5 and to provide a marginal rearwardly-projecting flange 8, which extends across the edge of the body. The inner or nose-engaging surface of the 80 facing is shown as roughened in the usual manner, for more secure engagement with the nose, while the flange 8 is smooth.

The facing-member, as just described, may 85 be formed in any preferred manner, but it is 90 most readily and inexpensively formed by punching and pressing sheet-material of suitable thickness. The punching and pressing operations may be performed by a single 95 pair of tools or dies and at a single operation, the material in the case of celluloid, being warmed to increase its plasticity. The recesses and projections on the roughened 100 surface may be formed upon the sheet, before the punching and stamping operation, but they are preferably formed by means of 105 the pressing-dies, thus further simplifying and cheapening the manufacture of the device. The angle 9 between the inner surface of the facing and the flange 8 is free from sharpness or roughness, since it is formed by bending the material and not by the 110 shearing operation, and it may be rounded as much as is desirable by a suitable formation of the dies, though a fairly definite angle is preferable for the sake of a secure engagement with the nose.

The marginal flange on the facing-member assists the operation of assembling the parts, since it automatically secures correct registration between them during the operation of riveting, and to secure this advantage and the advantage of avoiding a sharp and rough angle, only a slight rearward projection or narrow flange is necessary. Preferably, however, the flange is made wide enough to substantially or entirely cover the edge of the metal, so as to conceal this edge and thus produce a neat finish regardless of any roughness which may be produced in the metal in the shearing operation by which the metal is formed. In this connection the invention has a particular value in the manufacture of eye-glasses of gold-filled material or gold-plated sheet-metal. As shown in Fig. 3, the body 5 may be made of a comparatively thick sheet 10 of base-metal provided with a facing or plating 11 of gold. In nose-clamps as previously manufactured of such material the gold-facing or plating does not cover the sheared edge of the sheet-metal, and accordingly the base-metal is particularly subject at the edge to corrosion by the moisture of the skin. In the present construction the flange 8 may be formed to completely cover and protect the edge of the base-metal, so that it is invisible and is, to a large degree, protected from such corrosion.

In addition to the advantages of the novel facing of the present invention which have previously been pointed out, this facing has the further advantage that the rigid marginal flange contributes substantially to the security and permanency of the attachment between the facing and the body of the nose clamp. Where a facing of hard and comparatively rigid material, such as celluloid, is affixed to a metal body of irregular or curvilinear form, such, for example, as that

shown in Fig. 1 of the drawings, it is difficult to maintain the facing and the body with their edges in alinement, particularly as the nose-clamp is liable to be bent, either through the strains incident to use, or in order to adapt it to fit snugly against the nose of the wearer. Since there is no cement by which such rigid and impervious materials as celluloid and metal can be securely and permanently fastened together, the parts are usually fastened by rivets, as shown and described in the present application, and whenever the nose-clamp is bent as just described relative displacement of the parts in their plane of contact is liable to occur at the long disconnected portions between the rivets or points of attachment. Such displacement is positively prevented, however, in the present construction by the engagement of the rigid outwardly-projecting flange on the facing with the edge of the metal-body, so that the parts remain in proper relation notwithstanding all of the vicissitudes of use, and without the necessity of fastening them together otherwise than by riveting in the usual manner.

I claim:—

In a nose-clamp for eye-glasses, the combination, with a substantially flat sheet-metal body with square edges, of a facing, of hard plastic material, fitted against the inner surface of the body and molded to provide an outwardly projecting marginal flange which closely embraces the edges of the body and extends substantially flush with the outer surface of the body; and mechanical fastenings connecting the body and the facing at points inside their perimeters.

GUSTAV A. BADER.
